CLAIM

The ornamental design for a surface cleaning device as shown and described.

DESCRIPTION

FIG. 1 is a perspective view of an embodiment of my new design of a surface cleaning device;

FIG. 2 is a front view, the rear view is a mirror image thereof;

FIG. 3 is a side view, the opposite side view is a mirror image thereof;

FIG. 4 is a top view thereof; and,

FIG. 5 is a bottom view thereof.

The broken lines shown in the Figures are for the purposes of illustrates portions of the surface cleaning device, which form no part of the claimed design.

The surface cleaning device is shown with a symbolic break in its length using dot dash lines. The appearance of any portion of the article beyond the solid break forms no part of the claimed design.

1 Claim, 5 Drawing Sheets
